UNITED STATES PATENT OFFICE

2,028,214

SOAP EJECTING SPRAY HEAD

Mark M. Hennessy, Wauwatosa, Wis., assignor to
 Durant Manufacturing Co., Milwaukee, Wis., a
 corporation of Wisconsin

Application May 31, 1934, Serial No. 728,371

9 Claims. (Cl. 299—84)

This invention relates to improvements in soap ejecting spray heads.

Heretofore, beauty parlor operators and barbers, when shampooing a patron's hair, have been forced to utilize soap from a separate bottle or cake; and it has been necessary to first apply the soap, then replace the bottle or cake of the latter, and then pick up the water spray head. This inconvenient change must be made several times before the shampoo is completed. In the application of F. E. Pearl, Serial No. 712,703, there is disclosed a spray head having means embodied therein for discharging soap when desired, said means including a valve for controlling the flow of soap by gravity.

It is one of the objects of the present invention to improve upon the structure of the above-mentioned application by providing novel piston operated means for forcibly ejecting the soap.

20 A further object of the invention is to provide in a device as above described means for automatically breaking the vacuum which is created in the soap measuring chamber when the piston is being returned to normal position after soap 25 has been ejected.

A further object of the invention is to provide means for adjusting the length of the stroke of the piston to permit discharge of soap in measured amounts.

30 A still further object of the invention is to provide in a soap ejecting spray head having a nozzle located in the apertured water spray plate, means for preventing soap from said nozzle from contacting the plate to clog the apertures thereof.

35 A further object of the invention is to provide a device of the class described which is simple to fill with soap, simple to operate, and well adapted for the purpose specified.

With the above and other objects in view, the 40 invention consists of the improved soap ejecting spray head and all its parts and combinations as set forth in the claims and all equivalents thereof.

In the accompanying drawing illustrating one 45 complete embodiment of the preferred form of the invention, in which the same reference numerals designate the same parts in all of the views:

Fig. 1 is a vertical, sectional view thru the 50 spray head;

Fig. 2 is a cross-sectional view taken on line 2—2 of Fig. 1;

Fig. 3 is a fragmentary, vertical, sectional view showing the position of the piston at the start of 55 its downward stroke;

Fig. 4 is a similar view showing the positions of the parts when the piston has been moved sufficiently far to cause discharge of soap from the nozzle; and

Fig. 5 is a similar view showing the position of 5 the parts as the piston is being returned to normal position.

Referring more particularly to the drawing, the main housing, indicated by the numeral 8, is preferably substantially bell shaped, its lower 10 end being normally closed by a dished plate 9 formed with a plurality of apertures 10 and with a larger central opening 11 located in a depression 12. The apertures 10 are for the discharge of 15 water in shower form, and the aperture 11 is for the reception of a soap-ejecting nozzle 13, said nozzle being enlarged on the inside of the plate, as at 14, and being exteriorly threaded.

The peripheral edge of the plate 9 is flanged around the flared, lower edge 15 of the housing, 20 as at 16, and the parts are then pressed together to maintain the plate 9 firmly in position.

At an intermediate point within the housing is a horizontal partition 17 having a central opening 18 and an additional opening 19. A water inlet 25 pipe 20 has its lower end suitably affixed to the partition 17 with the opening of the pipe in registration with the opening 19 of the partition. The upper end of the pipe 20 extends thru the upper end of the housing 8 and is formed with 30 a shoulder 21 and a nipple 22 for the reception of one end of rubber tubing or the like 23. Below the shoulder 21 the pipe is preferably threaded for cooperation with a lock nut 24.

The upper end of the housing 8 is formed with 35 an opening 25 which is in alignment with the opening 18 of the partition 17. A sleeve 26 extends between the openings 18 and 25 and has a lower portion of decreased exterior diameter extending thru the opening 18 and formed to cooperate with the threaded enlarged portion 14 of the nozzle 13. The upper end of the sleeve 26 is also of decreased exterior diameter and projects exteriorly of the opening 25, said projecting portion being threaded to receive a nut 27. 40 A suitable sealing ring 28 may surround the sleeve beneath the partition 17.

A cap 29 is threaded on the upper end of the sleeve 26, and said cap is formed with a depending guiding sleeve 30 within which a plunger 31 50 is slidable, said plunger being formed with a suitable button 32 on its upper end. A packing nut 33 surrounds the plunger 31 below the guiding sleeve and is threaded on the latter.

A piston 34 is movable in the sleeve 26, and 55

the lower end of the plunger 31 is threaded in the upper end of said piston, there being a nut 35 for locking the plunger in fixed position with respect to the piston. By loosening said nut, the length of the stroke of the plunger may be varied.

The piston 34 is provided near its upper end with a peripheral recess 36, there being a transverse duct 37 extending from said peripheral recess to a central, longitudinal duct 38. The latter duct communicates with an enlarged chamber 39 for a ball valve 40, said ball being normally held in closing position with respect to the lower end of the duct 38 by a spring 41, the lower end of the spring being supported by a nut 42 having an aperture 43 therein.

In the lower end of the sleeve 26 is a chamber 44 for a ball valve 45. Said chamber communicates with the soap-ejecting nozzle 13. A spring 46 within said chamber normally holds the ball valve 45 in closing position. The upper end of the chamber 44 above the valve communicates with an enlarged soap measuring chamber 47, there being a spring 48 disposed within said chamber against which the piston is adapted to act.

Above the partition 17 the sleeve 26 is formed with a port 49 which permits soap from the soap reservoir 50 to flow into the soap measuring chamber 47 when the piston is in the position of Fig. 1 to expose said port. Near its upper end the sleeve 26 is formed with over-flow ports 51 for a purpose to be hereinafter described.

To fill the device with soap the cap 29 is unthreaded to permit withdrawal of the plunger and piston. Liquid soap may then be poured into the sleeve 26. Said soap will first fill the soap measuring chamber 47 and will then over-flow thru the port 49 and the over-flow ports 51 into the soap storage chamber 50. It is desirable to fill said chamber 50 to a level beneath the over-flow ports 51, as shown in the drawing, so that a certain amount of air is present in the upper portion of the casing. The piston is then re-placed in the sleeve and the nut 29 threaded in place.

In use, the device is held over the patron's head in the usual manner, the tube 23 being connected to a suitable supply of water. When the water is turned on, it will flow thru said tube into the conduit 20 and into the chamber below the partition 17. The water will then emerge in the form of a spray from the apertures 10 of the water spray plate 9. After the patron's head has been sufficiently moistened, the water may be shut off and the plunger 31 depressed to cause ejection of a supply of soap from the nozzle 13. Before the plunger is depressed, the piston and valves are in the position shown in Fig. 1, the soap measuring chamber 47 being filled with liquid soap. When the piston has been moved sufficiently far to close the port 49, the parts will be in the position shown in Fig. 3, with the ball valve 45 still in closing position. Upon further movement, however, enough pressure will be created on the soap to cause opening of the ball valve 45 against the tension of the spring 46, as shown in Fig. 4. This will necessarily cause ejection of soap. After soap has been ejected, the spring 48 will cause automatic return of the plunger to normal position. However, said action will set up a vacuum in the soap measuring chamber, and ordinarily this vacuum would retard the return of the piston. To eliminate this trouble, an automatic air intake has been provided. When this

vacuum is created as the plunger is being returned, the vacuum will cause opening of the ball valve 40, as shown in Fig. 5. This will admit air from the peripheral recess 36 thru the transverse port 37, longitudinal port 38, and chamber 5 to break the vacuum within the soap measuring chamber 47 and thereby permit quick return of the plunger and piston to normal position. The peripheral recess 36 receives its supply of air thru leakage along the side of the piston from the space thereabove, and the air is supplied to said space from the air above the soap level in the soap chamber thru the medium of the ports 51.

As before mentioned, adjustment of the length of the stroke of the plunger may be readily effected by loosening of the nut 35 and turning of the plunger one way or the other, as desired. This will permit measuring of the amount of soap to be discharged.

As the soap is discharged from the nozzle 13, if the end of said nozzle were in contact with the plate 9, soap would be likely to contact the plate and flow over the surface thereof to clog the water apertures. Accordingly, the nozzle is so formed as to project from the central depression 12 to eliminate this possibility.

As in the application of F. E. Pearl, before mentioned, it will be seen that the water conduit 20 first passes thru the soap storage chamber to warm the latter so that it will be at such temperature as to not subject the patron to the discomfort of temperature differences between the soap and water. Furthermore, this warming of the soap tends to permit free flow thereof.

From the above it may readily be seen that a very positive and effective means has been provided for forcibly ejecting soap from a water spray head, and it may further be seen that the action of the piston is positive, even in the return direction, due to the provision of means for breaking the vacuum therein.

Altho only one form of the invention has been shown and described, it is obvious that various changes and modifications may be made without departing from the spirit of the invention; and it is to be understood that all such changes are contemplated as may come within the scope of the claims.

What I claim is:

1. A soap ejecting spray head comprising a casing having one end apertured, means for admitting water to said casing for discharge in the form of a spray from said apertures, a soap nozzle in the apertured end of said casing, a soap chamber within the casing sealed from the water within the casing and communicating with said nozzle, and piston means for controlling the discharge of soap independently of the water from said soap chamber through said nozzle.

2. A soap ejecting spray head comprising a casing having one end apertured, means for admitting water to the casing for discharge in the form of a spray from said apertures, a soap nozzle in the apertured end of the casing, a soap storage chamber in the casing, a conduit between the soap nozzle and the soap storage chamber, a pressure actuated valve controlling the flow of soap from said conduit to the nozzle, and a piston movable in said conduit to cause pressure upon the soap therein to open said valve and permit ejection of said soap.

3. A soap ejecting spray head comprising a casing having one end apertured, means for admitting water to the casing for discharge in the form of a spray from said apertures, a soap noz-

zle in the apertured end of the casing, a soap storage chamber in the casing, a conduit between the soap nozzle and the soap storage chamber, a pressure actuated valve controlling the flow of 5 soap from said conduit to the nozzle, and a piston movable in said conduit, said piston being so positioned as to first shut off communication between the conduit and the soap storage chamber when the piston is depressed and then to 10 cause pressure upon the soap in the conduit and opening of the valve to permit ejection of said soap.

4. A soap ejecting spray head comprising a casing having one end apertured, means for admitting water to the casing for discharge in the form of a spray from said apertures, a soap nozzle in the apertured end of the casing, a soap storage chamber in the casing, a conduit between the soap nozzle and the soap storage chamber, 15 a pressure actuated valve controlling the flow of soap from said conduit to the nozzle, a piston movable in said conduit to cause pressure upon the soap therein to open said valve and permit ejection of said soap, said piston having an air duct 20 therein, yielding means for returning said piston to normal position, and an automatically operable valve in connection with said air duct for admitting air to the conduit to break the vacuum therein when the piston is being returned to 25 normal position.

5. A soap ejecting spray head comprising a casing having one end apertured, means for admitting water to the casing for discharge in the form of a spray from said apertures, a soap nozzle in said apertured end of the casing, and means for causing independent discharge of soap from said nozzle, the apertured end of the casing being recessed around the end of the nozzle to prevent soap from contacting the casing end and clogging the apertures thereof.

6. A soap ejecting spray head comprising a casing having one end apertured, means for admitting water to the casing for discharge in the form of a spray from said apertures, a soap nozzle in said end of the casing, a sleeve extending from said soap nozzle to the opposite end of the casing and there having an end opening communicating with the exterior, a piston operable in said sleeve, a plunger extending from said piston through the open end of the sleeve, means through which said plunger is slidale for removably closing the open end of the sleeve, a soap storage chamber in the casing having a port in communication with a portion of the sleeve to feed soap thereto, said port being so positioned as to be closed by the piston upon movement of the latter, and a pressure operated valve controlling the flow of soap from the soap nozzle.

7. A soap ejecting spray head comprising a casing having one end apertured, means for admitting water to the casing for discharge in the

form of a spray from said apertures, a soap nozzle in said end of the casing, a sleeve extending from said soap nozzle to the opposite end of the casing and there having an end opening communicating with the exterior, a piston operable in said sleeve, 5 a plunger extending from said piston through the open end of the sleeve, means through which said plunger is slidale for removably closing the open end of the sleeve, a soap storage chamber in the casing having a port in communication with a portion of the sleeve to feed soap thereto, said port being so positioned as to be closed by the piston upon movement of the latter, a pressure operated valve controlling the flow of soap from the soap nozzle, yielding means for returning said 10 piston to normal position, and means for automatically breaking the vacuum in the sleeve during said return.

8. A soap ejecting spray head comprising a casing having one end apertured, means for admitting water to the casing for discharge in the form of a spray from said apertures, a soap nozzle in said end of the casing, a sleeve extending from said soap nozzle to the opposite end of the casing and there having an end opening communicating 15 with the exterior, a piston operable in said sleeve, a plunger extending from said piston through the open end of the sleeve, means through which said plunger is slidale for removably closing the open end of the sleeve, a soap storage chamber in 20 the casing having a port in communication with a portion of the sleeve to feed soap thereto, said port being so positioned as to be closed by the piston upon movement of the latter, a pressure operated valve controlling the flow of soap from 25 the soap nozzle, and means in connection with the plunger for varying the length of the stroke of the piston to provide for the ejection of measured amounts of soap.

9. A soap ejecting spray head comprising a casing having one end apertured, means for admitting water to the casing for discharge in the form of a spray from said apertures, a soap nozzle in said end of the casing, a sleeve extending from said soap nozzle to the opposite end of the casing 40 and there having an end opening communicating with the exterior, a piston operable in said sleeve, a plunger extending from said piston through the open end of the sleeve, means through which said plunger is slidale for removably closing the open 45 end of the sleeve, a soap storage chamber in the casing having a port in communication with a portion of the sleeve to feed soap thereto, said port being so positioned as to be closed by the piston upon movement of the latter, and a pressure operated valve controlling the flow of soap 50 from the soap nozzle, said plunger and piston being removable from the sleeve to provide for filling of the soap storage chamber from the open 55 end of the sleeve.

MARK M. HENNESSY. 60
